UNITED STATES PATENT OFFICE.

JULIUS I. LEVETT, OF NEW YORK, N. Y.

GARBAGE-CAN.

1,240,740.

Specification of Letters Patent. Patented Sept. 18, 1917.

Application filed December 14, 1916. Serial No. 136,972.

To all whom it may concern:

Be it known that I, JULIUS I. LEVETT, a subject of the Czar of Russia, and a resident of the city of New York, borough of Manhattan, in the county and State of New York, have invented a new and Improved Garbage-Can, of which the following is a full, clear, and exact description.

Among the principal objects which the present invention has in view are: to confine disagreeable odors and fumes; to prevent accidental dislodgment of the cover; to avoid handling the garbage; and to furnish the structure with a simple and efficient means for carrying the receptacle.

Drawings.

Figure 1 is a vertical section of a can of the character mentioned constructed and arranged in accordance with the present invention. In said figure the full lines show the inactive disposition of the parts of the can, while the dotted lines show the active position of said parts;

Fig. 2 is a top plan view on diminished scale, showing the can disposed to receive garbage.

Description.

As seen in the drawings, the body of the can is a tubular cylinder 7. A fixed canopy 8 is attached to the cylinder 7, a flange 9 being provided for this purpose. The canopy 8 is shaped to form a globular section, the forward open edge 10 whereof is adjacent the median line of the cylinder 7 and sloped rearwardly therefrom. Partially surrounding the open edge of the canopy 8 is a stop 11 against which, in service, a depressed edge 12 of the cover 13 rests. When the edge 12 engages the stop 11, the opening edge 14 of the cover 13 is disposed below the upper edge 15 of the cylinder 7.

In the closed position of the cover 13, the inner surface thereof rests upon, in support relation to, the edge 15. The result of the closure of the cover 13 on the edge 15 and stop 11, is that fumes, odors, or gases generated in the contents of the can are held imprisoned therein.

The cover 13 is globular in form and is provided laterally with hinge lugs 16, which are connected by hinge pins 17 permanently with the cylinder 7.

When the cover 13 is retracted to the position shown in Fig. 2 and by dotted lines in Fig. 1 of the drawings, the said cover and

lugs 16 swing on the pins 17 until the edge 12 rests on the side of the cylinder 7. The weight of the cover 13 is carried by one side of the pins 17 and therefore remains in the position in which it is placed without further assistance or restraint. For moving the cover to and from its open and closed position, it is provided with a handle 18.

The lugs 16 are rigidly mounted on the cover 13 by rivets 19. Above the junction of the lugs 16 and cover 13, the lugs are bent to form bail ears 20.

Pivottally connected with the ears 20 is a bail 21. The bail 21 is employed for locking the cover 13 in closed position on the can, and for carrying the can. The bail 21 is bowed and is so constructed that when thrown forward it swings over a handle 22 and springs into a recess formed by an offset 23 in the said handle. The bail when latched in this position exerts a pull on the lugs 16 and ears 20 thereof which holds the edge 12 of the cover 13 firmly against the stop 11. The engagement between the bail 21 and the handle 22 is sufficient to prevent the accidental dislodgment of the said bail and the consequent release of the cover 13.

When, however, it is desired to utilize the bail 21 for transporting the can, it is released from the handle 22, and placed in the vertical position shown in Fig. 1 of the drawings, where it is obvious that the lifting strain exerted on the pins 17 does not result in dislodging the cover 13 from its active or closure position on the can.

When it is desired to place any article in the can, the bail 21 is thrown back of the can to the position shown at the right of Fig. 1 of the drawings. In this position the cover 13 is free to be thrown back, the operator using the handle 18 for this purpose.

When it is desired to empty the can, the bottom 24 thereof is allowed to swing on the hinge pin 25 to the position shown by dotted lines in Fig. 1 of the drawings. This is accomplished by depressing the tail-piece 26 of a latch 27 to lift the latch head 28 from engagement with the rim 29 of the bottom 24. The rim 29 is formed at the upper edge of a standing flange 30 with which the said bottom is furnished.

The latch 27 is normally held engaged with the rim 29 by a spiral spring 31, which spring is interposed between the tail-piece 26 and the side of the cylinder 7. To guide

the spring 31, a post 32 is extended through the said spring and through a slot 33 formed in the said tail-piece.

It is obvious that when the can is lifted by means of the bail 21, the operator by pressing on the tail-piece 26 will release the bottom 24, permitting the same to drop to a vertical position to dump the contents of the can. It is equally obvious that after 10 having so dumped the contents of the can, the bottom of the same may be closed by bringing the said bottom to the horizontal position, the rim 29 thereof displacing the head of the latch 27 until the said rim passes 15 the head 28 thereof, when by the operation of the spring 31, said latch secures the said bottom in service position.

After the can has been placed in position to have garbage placed therein, the operator may by means of the handle 18, retract the cover 13 to the position shown in Fig. 2 of the drawings, exposing the interior of the can to receive the contents destined therefor. This having been accomplished, 20 the cover is drawn to the position shown in Fig. 1. The bail 21 is now lowered to engage the handle 22 and the groove in the offset 23 thereof. The groove holds the

bail in position and said bail prevents the rearward swing of the lugs 16 and the cover 30 35 connected therewith. In this way the cam is closed to prevent the escape of odors or other disagreeable emanations except when and as the cover is lifted for the deposit of garbage therein.

Claims.

1. An article as characterized comprising an open-ended cylindrical body; a cover pivotally connected with said body at points 40 concentric with the path of movement of said cover; and a bail pivotally connected with said cover above the pivotal mounting thereof, said bail being arranged for engaging said body when said cover is closed.

2. An article as characterized comprising an open-ended cylindrical body; a cover pivotally connected with said body at points 50 concentric with the path of movement of said cover; a bail pivotally connected with said cover above the pivotal mounting thereof, said bail being arranged for engaging said body when said cover is closed; and means for locking said bail in engaged relation to said body.

JULIUS I. LEVETT.
